[57] CLAIM

The ornamental design for a combined digital audio disc
player, radio receiver, amplifier and tape recorder, as
shown and described.

DESCRIPTION

FIG. 1 is a plan view of combined digital audio disc
player, radio receiver, amplifier and tape recorder
showing our new design;

FIG. 2 is a bottom view thereof;

FIG. 3 is a front view thereof;

FIG. 4 is a rear view thereof;

FIG. 5 is a left side view thereof;

FIG. 6 is a right side view thereof; and,

FIG. 7 is a perspective view thereof in a state where
cassette lids are opened and a disc tray is drawn out.

[73] Assignee: **TEAC Corporation**, Tokyo, Japan

[**] Term: **14 Years**

[21] Appl. No.: **753,692**

[22] Filed: **Sep. 3, 1991**
